York, N. Y., a corporation of New Jersey

Application May 5, 1931, Serial No. 535,191

6 Claims. (Cl. 177—314)

The present invention relates to an electrical alarm system, and has for its primary purpose the provision of a room, or vault alarm having the dual function of providing said room or vault with alarm means against fire, or burglarizing, to give visible or audible warning in the event of fire or unauthorized entry, or both.

The device comprehends the use of the Wheatstone bridge principle, so modified as to create an accurate, alarm initiating means, of great sensitivity and having therein a fixed, predetermined set of resistances, single or plural, in each leg of the bridge, so that normally at all times except at the moment of functioning by the noted disturbances, the bridge is in electrical balance in all legs thereof, and therefore is normally quiescent.

The numbers of resistances or pairs of resistances in each leg of the bridge may be unequal or equal, and may be multiplied to suit the number of required stations installed in a zone to be protected, as will be more specifically set out in detail, hereinafter.

Further, the single or paired resistances are so arranged and selected that each element of any element or pair, in any leg, are of unlike temperature coefficients. This will be better understood by stating as will hereinafter be described, relative to the drawings, that any one element of any leg or pair of resistances may be of a carbon filament, or wire, which has a temperature coefficient of minus .0005 ohms per degree centigrade, while the other element of such leg or pair may be a tungsten filament or wire which has a temperature coefficient of plus .0089 ohms per degree centigrade.

The differences above noted, therefore, become the means whereby the associated alarm system becomes operative, upon sudden local temperature changes within the zone or room. These sudden, local temperature changes, as will be later pointed out, cause a state of unbalance in the Wheatstone system and cause the alarm to function.

Gradual room temperature changes affecting all of the sensitive elements of the bridge, either of depressed or raised room temperature, will not cause the system to initiate an alarm, thus the device will automatically compensate itself for varying general or average room temperatures, plus or minus, but at all times sensitive to sudden local temperature changes or rises, from any maximum or minimum self-compensated temperature point or condition.

It will be obvious from the foregoing and as

the description proceeds, that variations may be made in the material of the paired resistance elements, their mode of distribution within a room, or the form of alarm means may be varied, from the herein described device, or the scope of the appended claims, without departing from the principles of the system as herein outlined.

In the drawings, diagrams are entirely resorted to throughout, as the best and simplest method of outlining the device as herein disclosed, and, further, all like parts and elements have the same indices, for brevity, convenience and easier understanding.

Fig. 1 shows a simple form of the device and diagrammatically outlines a Wheatstone bridge modified to illustrate the main principles of the present invention;

Fig. 2 shows a translating means including an alarm and an alarm relay in connection with the alarm initiating galvanometer of such Wheatstone system;

Fig. 3 is a modified system showing a (one) set of control filaments in each leg of the bridge;

Fig. 4 is a sectional diagrammatic plan view of a room with the bridge system of Fig. 3 distributed at different points in such room with a distant bridge initiated alarm relay circuit connected thereto;

Fig. 5 is a further modified bridge alarm system showing plural (two) sets of pairs of control filaments in each leg of the bridge;

Fig. 6 shows a diagrammatic plan view of the protective distribution or location of such pairs of filaments in a room;

Fig. 7 is a still further modified bridge system showing a greater plurality of (three) sets of filament pairs in each leg of a bridge circuit;

Fig. 8 is a diagrammatic plan layout of one form of protective room disposition of the bridge layout of Fig. 7; and

Fig. 9 is a fragmentary elevational view of the door or entry to the room of Fig. 4, showing a relative location of a pair of the protective filaments of the bridge layout of Fig. 3 in room door protecting position.

As showing how this is accomplished, attention is called to Figs. 1, 2 and 4 in which the normally balanced Wheatstone bridge ABCD is shown. Each leg of any two adjacent legs C, D (or A, B, or A, C or B, D or of all of them) may comprise an exposed element c (c1, c2, c3 or c4) such as carbon having a negative temperature coefficient and an exposed element t (t1, t2, t3 or t4) such as tungsten having a positive temperature coefficient. A positive element (for instance

t_1) or each leg (as C) is closely adjacently associated with a negative element (as c_2) of the adjacent leg (as D) to form a station set up, as shown in Fig. 4 by the set-ups t_1, c_2, c_1t_2, t_3c_4 5 and c_3t_4 . Other combinations such as set-ups c_1t_2, c_2t_3, c_3t_4 and c_4t_1 or any number of them would be good. It is only necessary that the elements of different sign be in adjacent legs.

The station set-ups may be disposed in the upper part V of the room R at widely separated points to form stations, one of them being near the door V. The alarm 23 is operated by said bridge when the bridge becomes unbalanced. Corresponding elements as t_1, t_2 or t_2, t_3 of each 10 pair of adjacent legs may be substantially equal in length, diameter and radiating coefficient, whereby the bridge remains balanced whenever the temperatures at the stations remain equal, even should the temperatures at all stations 15 change equally and suddenly. However change of temperature at one station as c_1t_2 relative to another c_3t_4 causes a decrease of resistance in one of said adjacent legs and an increase in the other, whereby the bridge becomes doubly unbalanced and greatly unbalanced on a slight difference 20 in temperature, and the alarm is thereby operated.

Fig. 1 shows a broader aspect of the invention, showing that only one resistance need be in each 25 leg. Thus the bridge of Fig. 1 may provide two stations, as by bringing resistances, c_1, t_2 together as in the upper right of Fig. 4, and bringing together resistances c_3t_4 as in the lower right of Fig. 4.

So long as the room temperature is relatively uniform at the stations, the bridge remains balanced; but if the temperature at set-up c_1, t_2 becomes not the same as at set-up c_3, t_4 , the bridge 30 becomes unbalanced, and the alarm operates.

As a continuation of the system herein disclosed there is shown in Fig. 2, an alarm circuit and relay, for giving warning of either entry, or undesired temperature changes within the protected zone. To this end the galvanometer G and 35 the two contact switches s are again shown, as in Fig. 1, with the connections E, F, indicated, but with a relay coil operating wiring circuit 7, 8, 9, 10, one end of which as at 7 is connected to the switch s the other end of said circuit, as 10, being connected to the galvanometer needle. A current source 11 is connected into this circuit, and upon operation of the galvanometer needle to close upon switch s, the coil 12 is actuated to draw armature 16 upon pivoted switch lever 13, upward 40

upon its pivot 14, and thus close contacts 17-18 thereby actuating alarm circuit 19-20, 21, in which is mounted and connected an alarm 23 and a source of current supply 22. The lever 13 is normally stressed by a pin held spring 15 to remain open until the coil 12 actuates it. This alarm relay means is also shown in Fig. 4 with the same indices as above described.

Thus under normal conditions of the bridge circuit the alarm relay gives no alarm, but upon any change of balance in the bridge circuit the alarm is caused to give warning.

To accomplish this, reference may be had to Fig. 1. In this figure, in leg A, is shown a resistance element c_3 in heavy lines to represent a carbon filament. In leg B is shown a resistance element t_4 , in light lines to represent a tungsten filament. In leg C is shown a carbon filament c_1 in heavy lines, while in leg D is shown a resistance element t_2 in light lines. This heavy and light lining to represent carbon and tungsten ele-

ments in the various legs of all Wheatstone bridge diagrams shown herein is adhered to throughout, and the indices c and t to indicate carbon or tungsten elements is also utilized where a plurality of such elements are utilized in each leg is also 5 adhered to with changed exponents, to identify each added resistance element of a leg group.

Obviously, with an arrangement as set out in Fig. 1, sudden local temperature changes affecting any of the filaments c or t in any leg cause the 10 galvanometer G to deflect its needle and cause an alarm. Normal rises or depressions of temperature affecting all of the c and t elements, such as would normally occur in a closed room or protected zone, will not disturb the equilibrium 15 of the bridge circuit.

As a better illustration of the idea, Fig. 3 discloses a bridge circuit identified and exactly like that as described for Fig. 1, with the exception that each leg of the bridge A, B, C, D, 20 has an added resistance element therein of opposite characteristics. Whereas, in Fig. 1, legs A, B, C, D, have elements c_3, t_4, c_1 and t_2 respectively, these same legs in Fig. 3, have elements $c_3+t_3, t_4+c_4, t_1+c_1$, and c_2+t_2 respectively. 25

Thus in Fig. 3 each leg has a balancing pair of thermally sensitive elements comprising a carbon and tungsten pair in each leg.

The purpose of this latter structure, in one form of installation is exemplified in Fig. 4 in 30 which there is disclosed a diagrammatic plan of a room or zone to be protected against sudden temperature disturbances, such as a fire within, or the entry of an individual who may move about said room thereafter. Thus, the confines 35 of the zone are shown by the walls R, and in which is a door or point of entry V, and in which is located a Wheatstone bridge circuit and a preferably external and distant alarm system. The indices and functions of the parts of the various 40 elements are like those as previously described, and it is thought need no further detailed identification or explanation.

Thus Fig. 4 shows that by reason of there being two c and t elements in each leg of the bridge, it 45 is possible to control by proper distribution through the protected zone, a four station set up, as shown in each of the four corners of Fig. 4. As thus shown, each station set up comprises a c and t couple of each leg of the bridge system, as will be noted by the indices thereon.

Obviously, the location of the c and t couples in Fig. 4 are disposed at room distances from one another, to such an extent that general temperature conditions within the room keep the bridge 55 system in a state of automatically compensated balance, and therefore in non-alarm condition. Such changes as may occur are gradual and affect all of the c and t elements simultaneously.

In Figs. 4 and 9, a pair of elements t_3 and c_4 60 are shown as being adjacent a door V. When normal conditions prevail within the zone or room R, any tendency to disturb those normal conditions such as opening the door V or a window or breaking through the wall of the room 65 cause a disturbance of the static conditions of the room atmosphere and thus create a sudden change therein.

In Fig. 9 there is shown a dotted line X which can indicate a line of demarcation between 70 stratas of room atmospheric temperatures, the upper strata Y above line X being a little warmer than the strata Z below line X. Undisturbed, the temperature of these stratas remain quite constant. Entry by opening the door causes admix- 75

ture of these quiescent stratas and affect door guarding couple, for instance, t_3 and c_4 , cause a state of unbalance in the bridge circuit and set off the alarm.

5 Further, it has been found that bodily movement of an individual, around the room cause air disturbances and temperature changes and thereby cause an alarm to be initiated. Even in rooms, not closed from other rooms, the passing there-through of an individual disturbs the normal equipoise of the bridge system and causes an alarm to be initiated.

10 A sudden increase in heat in the protected zone R will also affect the balance of the bridge circuit from whatever cause, though heat changes of a gradual nature from radiators or other room heating sources automatically cause the bridge system to compensate itself and thus keep all legs of the system in balance.

15 20 Satisfactory results are obtained if the tungsten element is about two thousandths of an inch in diameter with resistance of 60 ohms at 22° C., and the carbon element is about four thousandths of an inch in diameter with a resistance of 120 ohms at 22° C. A current flow through the battery of three tenths of an ampere renders the elements operatively sensitive to motion or disturbance within a radius of 10 to 12 feet. A current flow of four tenths amperes renders the system much more sensitive than required.

25 It is understood however that the invention is not limited to the particular designs and specifications herein indicated.

30 In order to increase the number of stations in any installation it is only necessary to provide additional c and t elements in each leg, this being illustrated fully in Figs. 5 and 7, the zone distribution being shown in Figs. 6 and 8 respectively. Thus in Fig. 5 the sets of c and t elements as used in Fig. 6 may be outlined as follows:

Set #1, t_1 , c_2 , t_4 , c_3 .

Set #2, c_1 , t_2 , c_4 , t_3 .

Set #3, t_1' , c_2' , t_4' , c_3' .

45 Set #4, c_1' , t_2' , c_4' , t_3' .

Thus, the arrangement set out for Figs. 5 and 6 show arrangements of couples in four sets of control elements of four elements each. More or less may be used.

50 55 Again in Figs. 7 and 8 there are set forth a six element group for each leg of the bridge, Fig. 8 showing six sets of station distribution of four elements each. It is thought that, by reason of the explanation set out for the preceding figures that a detailed outline of the set distribution of Figs. 7 and 8 are unnecessary.

60 It is obvious, therefore, that owing to the spaced distribution, in a protected zone, of the c and t elements as hereinbefore outlined, that we have provided a novel and efficient alarm system, self compensating, under normal temperature change conditions, against a state of unbalance, but extremely sensitive to sudden local temperature changes, from any cause to cause a state of unbalance and thereby initiate a warning thereof.

65 It is obvious, also, that other groupings of the c and t elements may be utilized, in a greater number of distributed control stations than herein outlined, and that other sensitive elements having divergent temperature co-efficients may be substituted for the carbon and tungsten resistance elements herein outlined.

Having thus described the invention, what is claimed is:

75 1. In combination, a normally balanced

Wheatstone bridge of which each of two adjacent legs comprises an element having a negative temperature coefficient and an element having a positive temperature coefficient; a positive element of one leg being closely adjacently associated with a negative element of the adjacent leg and remote from the other elements.

5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330

2. In combination, a normally balanced Wheatstone bridge of which each of two adjacent legs comprises an element having a negative temperature coefficient and an element having a positive temperature coefficient; a positive element of each leg being adjacently associated with a negative element of the adjacent leg to form a station set-up; a translating means controlled by the balance of said bridge; corresponding elements of the set-ups being substantially equal in resistance and radiating effect, whereby the bridge remains balanced if the temperatures at the stations remain equal.

3. In combination, a normally balanced system of which each of two balancing parts comprises an element having a negative temperature coefficient and an element having a positive temperature coefficient; a positive element of each part being adjacently associated with a negative element of the other part to form a station set-up; the set-ups being disposed at widely separated points; a translating means controlled by the balance of the system; corresponding elements of the set-ups being substantially equal in resistance and radiating effect, whereby the system remains balanced if the temperatures at the stations remain equal; change of temperature at one station relative to the other causing a decrease of resistance in one of said parts and an increase in the other part at the same station, whereby the system becomes considerably unbalanced on a slight difference in temperature.

35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330

4. In combination, a normally balanced Wheatstone bridge of which two adjacent legs each comprise an element having a negative temperature coefficient and an element having a positive temperature coefficient; a positive element of each leg being adjacently associated with a negative element of the adjacent leg to form a station set-up; a room having a door; the set-ups being disposed in substantially the same level of said room at widely separated points, one of them being near the door; a translating means controlled by the balance of said bridge; corresponding elements of the set-ups being substantially equal in resistance and radiating effect, whereby the bridge remains balanced if the temperatures at the stations remain equal; change of temperature at one station relative to the other causing a decrease of resistance in one of said adjacent legs and an increase in the other of the same station, whereby the bridge becomes considerably unbalanced on a slight difference in temperature.

5. In combination, a normally balanced Wheatstone bridge of which each of two adjacent legs comprises an exposed element such as carbon having a negative temperature coefficient and an exposed element such as tungsten having a positive temperature coefficient; a positive element of each leg being closely adjacently associated with a negative element of the adjacent leg to form a station set up; a room having a door; the station set-ups being disposed in an upper level of said room at widely separated points to form stations, one of them being near the door; and an alarm set off by said bridge when the bridge becomes unbalanced; corre-

- sponding elements of the set-ups being substantially equal in length, diameter and radiating coefficient, whereby the bridge remains balanced if the temperatures at the stations remain equal;
- 5 change of temperature at one station relative to the other causing a decrease of resistance in one of said adjacent legs and an increase in the other, whereby the bridge becomes considerably unbalanced on a slight difference in temperature
- 10 and the alarm is operated.
6. In combination, a normally balanced Wheatstone bridge of which two adjacent legs each comprise an exposed element having a neg-

ative temperature coefficient and an exposed element having a positive temperature coefficient; a positive element of each leg being closely adjacently associated with a negative element of the adjacent leg; a translating means; means controlled by the bridge for controlling the translating means when the bridge is changed from balanced to unbalanced condition and vice versa; said exposed elements and the bridge being sufficiently sensitive to a few degrees variation in temperature to control the translating means. 10
